UNITED STATES PATENT OFFICE.

THOMAS CASCADEN, JR., OF WATERLOO, IOWA, ASSIGNOR TO THE DAVIS GASOLINE ENGINE WORKS COMPANY, OF SAME PLACE.

DESIGN FOR A GRINDING-MILL BODY.

SPECIFICATION forming part of Design No. 33,558, dated November 13, 1900.

Application filed September 12, 1900. Serial No. 29,813. Term of patent 3½ years.

To all whom it may concern:

Be it known that I, THOMAS CASCADEN, Jr., resident of Waterloo, in the county of Black Hawk and State of Iowa, have invented and produced a new and original Design for Grinding-Mill Bodies, of which the following is a specification.

The accompanying drawing shows a perspective view of the design.

- o As appears in the drawing, the mill-body is provided with a cylindrical base A, having at its upper edge an outwardly-projecting flange a, to which at several points are bolted outwardly and downwardly curved legs B. Located on the base A are two cylindrical portions C and D, the upper of which is of smaller diameter than the lower. The lower cylindrical portion C is provided near its top with an outwardly-projecting flange c. Bolted to the upper cylindrical portion D is a short truncated cone E, having outwardly-project-

ed flanges e and e' at the bottom and top, respectively.

As shown, the upper portion of the mill-body consists of an inverted truncated-coned-shaped hopper F, secured to a ring f, which has an outwardly-projecting flange f', which rests upon and is secured to the flange e' of the part E.

Having thus described the invention, what I claim as new, and desire to secure by Letters Patent, is—

The design for a grinding-mill body, substantially as shown and described.

In testimony whereof I have signed my name in the presence of two subscribing witnesses.

THOMAS CASCADEN, JR.
